CLAIM

I claim the ornamental design for a guardian battery door, as shown and described.

DESCRIPTION

FIG. 1 is a perspective view of the design of the present invention for a guardian battery door;

FIG. 2 is a front elevation view of the guardian battery door of FIG. 1;

FIG. 3 is a side elevation view of the guardian battery door of FIG. 1;

FIG. 4 is a top view of the guardian battery door of FIG. 1; and,

FIG. 5 is a bottom view of the guardian battery door of FIG. 1.

The features of the guardian battery door shown in broken lines are for illustrative purposes only and form no part of the claimed design.
